UNITED STATES PATENT OFFICE.

GEORGE E. A. FAIRLEY, OF PITTSBURGH, PENNSYLVANIA.

PUZZLE.

Application filed April 10, 1925. Serial No. 22,203.

To all whom it may concern:

Be it known that I, GEORGE E. A. FAIRLEY, a citizen of the United States, residing at Pittsburgh, in the county of Allegheny and 5 State of Pennsylvania, have invented a new and useful Improvement in Puzzles, of which the following is a full, clear, and exact description.

This invention relates to puzzles, and particularly to that class of puzzles where the skill of the user is exercised in guiding a surface projectile to a given point.

I provide a puzzle including an iron surface projectile member and an iron barrier member, at least one of said members being magnetized. The puzzle preferably comprises a base having a rim for confining the projectile and provided within the rim with one or more iron barriers, these barriers being magnetized and having adjacent poles between which the projectile may be passed. For example, a barrier may be provided in the form of a substantially complete circle, the adjacent ends of the barrier forming the 20 poles of a magnet and the base being provided with a hole or holes between such poles for trapping the projectile.

The accompanying figure of drawing is a perspective view of the present preferred 30 embodiment of my invention.

In the illustrated embodiment of my invention, there is shown a base 2 which is made of wood or other suitable non-magnetic material provided with a substantially 35 plane surface 3 which is surrounded by a rim 4.

Lying on the surface 3 is an iron ring 5 having adjacent ends 6 and 7. The ring 5 is magnetized and the terminal portions 6 and 7 form the poles of the magnet. Within the ring 5 is a smaller ring 8 having terminal portions 9 and 10. The inner ring 8 is also magnetized and the portions 9 and 10 form the poles of this magnet. Within the 45 ring 8 is a hole 11 and the object of the puzzle is to so manipulate the base 2 as to cause one or more surface projectiles 12 to fall into the hole 11. When the game is started the projectiles, which are preferably 50 iron balls, are placed outside the ring 5, as shown in the drawing. The only way the projectiles can be moved inside the ring 5 is between the poles 6 and 7, and it will be found that the effect of the magnetic poles 6 and 7 on the projectiles renders the action 55 of the projectiles very erratic at this point.

A hole 13 is provided adjacent each of the poles 6 and 7, and this combined with the magnetic effect of the barrier ring makes it extremely difficult to get the ball inside the 60 ring. Continued working with the puzzle, however, will enable an observing user to convert the magnetic effect into an advantage, especially if more than one projectile is used, as it will be found that the projectiles 65 can be caused to adhere to the magnet sufficiently to cause them to sweep right over a hole 13 if the movement is accomplished with sufficient rapidity.

One inside the ring 5, the user must take 70 great care that the projectiles do not drop into openings provided within and adjacent such barrier. In the illustrated embodiment of the invention one such hole is indicated at 14. Holes 15 are placed between the holes 75 9 and 10 and correspond to the holes 13 of the outer barrier ring 5. With this combination of holes and the magnetic barrier, it will be found when the parts are properly proportioned that an entirely different 80 action is required to get the projectiles between the poles 6 and 7 than is required to move them between the poles 9 and 10 into the space around the pole 11. The use of 85 the barriers themselves as magnets makes a puzzle which is interesting and enjoyable, as the difficulties are greatly increased by the magnetic action of the barriers on the projectiles.

I have used the word "iron" herein as a 90 word of description and not of limitation, and it is intended to cover any material having magnetic properties. In use it is found that the projectiles 12 themselves become 95 magnetized and will not only cling to the barrier rings adjacent the poles, but will also tend to hang close to such rings at other points. This makes it extremely difficult to avoid the dropping of the projectiles into 100 the hole 14.

While I have illustrated a preferred embodiment of my invention, it will be understood that it is not limited to the form illustrated and described, as it may be otherwise embodied within the scope of the following 105 claims:

I claim:

1. A puzzle, including an iron surface projectile member, and an iron barrier member, at least one of said members being magnetized, substantially as described.

2. A puzzle, including a base, an iron sur-

- face projectile movable over the base, and an iron barrier mounted on the base, the barrier being magnetized, substantially as described.
5. 3. A puzzle, including a base, an iron surface projectile movable over the base, and an iron barrier mounted on the base, the barrier being magnetized, and having adjacent poles between which the projectile may be 10 passed, substantially as described.
4. A puzzle, including a base, an iron surface projectile movable over the base, and an iron barrier mounted on the base, the barrier being magnetized, and having adjacent 15 poles between which the projectile may be passed, the base having a hole therein between the poles for trapping the projectile, substantially as described.
5. A puzzle, including a base, an iron surface 20 projectile movable over the base, an iron barrier mounted on the base, the barrier being magnetized, and having adjacent poles between which the projectile may be passed, the base having a hole adjacent each 25 pole in the space between the poles for trapping the projectile, substantially as described.
6. A puzzle, including a base, an iron surface projectile movable over the base, a plurality 30 of iron barriers mounted on the base within one another, the barriers being magnetized and having adjacent holes between which the projectile may be passed, and the base having holes therein between the poles 35 of each barrier, substantially as described.
7. A puzzle, including a base, an iron surface projectile movable over the base, an iron barrier mounted on the base, the barrier being magnetized and having adjacent 40 holes between which the projectile may be passed, and a second barrier within the first,
- the barriers being spaced apart to provide a path for the projectile, the base having a hole therein adjacent the inner surface of the first mentioned barrier for trapping the projectile, substantially as described. 45
8. A puzzle, including a base, an iron surface projectile movable over the base, an iron barrier mounted on the base, the barrier being magnetized and having adjacent 50 poles between which the projectile may be passed, the base having a hole between the poles for dropping the projectile, and an inner barrier mounted on the base, the inner barrier being magnetized and having adjacent 55 poles between which the projectile may be passed, the inner barrier being spaced from the first mentioned barrier, the base having a hole between the poles of the inner barrier for trapping the projectile, substantially 60 as described.
9. A puzzle, including a base, an iron surface projectile movable over the base, an iron barrier mounted on the base, the barrier being magnetized and having adjacent 65 poles between which the projectile may be passed, the base having a hole between the poles for dropping the projectile, and an inner barrier mounted on the base, the inner barrier being magnetized and having adjacent 70 poles between which the projectile may be passed, the inner barrier being spaced from the first mentioned barrier, the base having a hole between the poles of the inner barrier for dropping the projectile and the 75 base also having holes adjacent the inner surface of the first mentioned barrier for trapping the projectile, substantially as described.

In testimony whereof I have hereunto set my hand.

GEORGE E. A. FAIRLEY.
